UNITED STATES PATENT OFFICE.

WILLIAM KAHLE, OF LOS ANGELES, CALIFORNIA.

AUTOMATIC DRILLING-TOOL.

1,034,368.

Specification of Letters Patent. Patented July 30, 1912.

Application filed April 21, 1910. Serial No. 556,863.

To all whom it may concern:

Be it known that I, WILLIAM KAHLE, a citizen of the United States, residing at Los Angeles, California, have invented a new and useful Automatic Drilling-Tool, of which the following is a specification.

Among the objects of this invention are to provide an automatic drilling tool operating upon the reciprocatory principle that will always strike an efficient blow of uniform force upon the bottom of the well being drilled; to provide such a tool that will operate in a smooth and even manner without jarring the walking beam or suspending pipes; and to provide, in combination with other features of the invention, means for automatically rotating the drilling tool so as to make the hole circular and truly vertical.

In combination with other valuable features, the tool is adapted to receive and conduct to the bottom of the well a supply of water under pressure to eject the excavated material at the top of the well.

Referring to the accompanying drawings which illustrate the invention,—Figure 1 is a side elevation of the cutter-supporting plunger and the sleeve around said plunger, said sleeve being broken away to show the spring for imparting the downward stroke to said plunger. Fig. 2 is a side elevation of the tool, the greater portion of the outer jacket being shown in mid-section. In this view the position of the plunger which carries the cutter is somewhat different from the position shown in Fig. 1. Fig. 3 is a longitudinal mid-section of the tool, the plunger not being sectioned. Fig. 4 is a broken view on a reduced scale, partly in section showing the operating means and the upper portion of the tool. Fig. 5 is an enlarged transverse section looking up from line w^s of Fig. 2.

Referring in detail to the drawings, the cutter 1 is fastened to the lower end of a plunger 2 around which extends a sleeve 3 carried by the usual suspending pipe 4. Said sleeve 3 is provided with two longitudinal diametrically opposite slots 5. Each of said slots is widened toward one side of its upper end to provide a shoulder 6 at that side of the slot, said slot terminating at its upper end beyond said shoulder in a curved cam face 7 inclining toward the shouldered side thereof. Plunger 2 is provided with a key 11 extending diametrically there-

through, the ends of said key projecting a short distance from the sides of said plunger. The end portions of said key fit loosely in the narrow portions of slots 5 and are adapted to rest on the shoulders 6 to support the cutter 1. 60

Around sleeve 3 is a jacket consisting of an outer tube 12 which extends nearly to the bottom of the well and fits within the hole being drilled, and an inner tube 13, the external diameter of which is desirably a little less than the internal diameter of tube 12. Said inner tube 12 is supported in fixed relation to the tube 13, desirably by 65 an enlarged portion 13' having screw-threaded engagement within the upper portion of the outer tube 12. The outer tube 12 extends farther down than the inner tube 13. The jacket comprised by these tubes 12 70 and 13 is provided in its inner tube or section 13 with longitudinal, diametrically opposite slots 14 which may be termed "grooves" with respect to the jacket considered as a whole inasmuch as they extend 75 only through the inner tube or section of the jacket. Each groove 14 is deflected at 15 at its upper end to form a cam face 16 which inclines in the reverse direction to the cam face 7 of the slot 5 in the plunger on the 80 same side of the tool. The portion 15 of each groove is made wider than the rest of the groove. By reason of the tube 13 being spaced slightly away from the wall of the outer jacket 12, the key 11 is given a 85 sufficient foothold at each end to guard it 90 sufficiently against escaping from the slots 14, and it will be seen that this is accomplished without making the tube 13 with a 95 thick cumbersome wall.

The outer cylinder 12 of the jacket keeps the key 11 in place so that the end portions of the key are always within the slots 14. Upon the end portions of the key 11 bears a compression spiral spring 17, said spring 100 having its upper bearing upon the lower end of the suspending pipe 4 which is screwed into the upper end of sleeve 3. It is, however, obvious that other means may be provided to form a bearing for the upper 105 end of the spring. The pipe 4 forms a portion of the well known means for raising and lowering the cutter. During the downward travel of sleeve 3, the lower portion of pipe 4 moves freely over the upper portion of the plunger 2. The outer jacket 110 comprised of tubes 12 and 13 keeps the sand

and mud off from reciprocating parts therewith.

In Fig. 4 a portion of the usual beam 21 is shown from the end of which is suspended 5 a turn-buckle 22 by means of a screw threaded rod 23. The lower end of the turn-buckle may be bored out to receive a collar 24 fastened in by pins 25. Said collar supports a swivel bolt or pin 26 provided with a 10 bail 27 connected with the upper section of pipe 4.

The plunger 2 may be hollow thus providing a passage 28 from end to end thereof, said passage being continued at 28' through 15 the cutter and opening out of the side of the cutter through an aperture 29.

Water may be conducted into the suspending pipe 4 by means of a hose 31 shown in Fig. 4, the water passing down through the 20 passages 28 and 28' and thence out the aperture 29 to loosen up or force out the excavated material.

Operation: Assuming the cutter 1 to be resting upon the bottom of the well, and the 25 plunger 2 in the position shown in Fig. 1, when the end of the walking-beam 21 descends the sleeve 3 suspended therefrom will be lowered until the cam faces 7 at the upper ends of the oppositely disposed slots 5 30 engage the end portions of the key 11 causing the sleeve 3 to rotate slightly to allow the key 11 to move across the cam faces to a position vertically above shoulders 6. If the cutter is not too firmly embedded in the 35 earth it may be rotated somewhat in the reverse direction. When the reverse movement of the walking beam causes the sleeve 3 to ascend, the latter operates as a pick-up device because the shoulders 6 pick up the 40 key 11 together with the plunger 2 and cutter 1, and the cutter plunger continues to move up against the opposition of spring 17 until the projecting end portions of key 11 engage the cam faces 16 of grooves 14 45 of the jacket. Said cam faces 16 then slide the key off from shoulders 6 and the cutter and plunger descend under the combined forces of gravity and the compression spring 17 at each descent striking a sharp blow of 50 uniform force upon the bottom of the well.

A slight step-by-step rotation will also be imparted to the jacket members 12 and 13. The cause of this step-by-step rotation of said jacket will be understood when it is 55 noted that the end portions of key 11 at all times project into the grooves 14 of the jacket, so that any force tending to rotate said key in a horizontal plane will also tend to rotate the jacket members 12 and 13.

60 When the sleeve 3 (which is suspended by means of the pipe 4) descends, the beveled shoulders 7 of the slots 5 in said sleeve strike the key 11 as best illustrated in Fig. 1. The direct effect of the impact is to rotate the 65 sleeve 3 but the reaction will also give a

slight rotation to the tool carrying spindle 2 and the jacket members 12 and 13. The jacket and tool will naturally descend a trifle on account of the jar caused by the impact, and this descending movement will assist in overcoming friction and will therefore aid the torsional movement which takes place at the same time.

I am aware that it is not broadly new to provide means for automatically lifting and releasing a drilling tool and causing the same to strike the bottom of a well under the action of a spring, but this invention is an advance step in the art to which it pertains by reason of the employment of a simplified construction to perform the functions just mentioned. A single key which extends 75 diametrically of the tool is employed to control all the operations of the cutter.

I claim:

1. In automatic drilling apparatus, a relatively stationary outer jacket adapted to fit within the hole being drilled, a tube (13) within said jacket, said jacket having interior threads and said tube having an enlarged portion provided with external threads to screw into the threads on the interior of said jacket, said tube being suspended by said enlarged threaded portion and provided with a narrow annular chamber therearound between the same and said jacket, a cutter, a reciprocatory plunger, to which said cutter is attached, a key carried by and extending diametrically through said plunger, a pick-up device to automatically pick up and release said plunger by means of said key, said pick-up device being provided with cam faces that strike said key when said device descends and thereby impart a step-by-step rotation to 105 said plunger and cutter, and means to raise and lower said pick-up device, said tube (13) having vertical guide slots that receive the ends of said key, the interior surface of said outer jacket preventing end- 110 wise displacement of said key and said slots in said tube causing the torsion of the pick-up device upon said key to impart a step-by-step rotation to said outer jacket into 115 which said tube is screwed.

2. In automatic drilling apparatus, a relatively stationary outer jacket adapted to fit within the hole being drilled, a tube within said jacket, said tube having an enlarged portion which is secured within said 120 jacket with a fit rendering said tube non-rotatable with respect to said jacket during operation, there being a slight space around said tube between the same and said jacket, a cutter, a reciprocatory plunger by which 125 said cutter is carried, a key carried by and extending diametrically through said plunger, a pick-up device to automatically pick up and release said plunger by means of said key, said pick-up device being provided with 130

cam faces that strike said key when said device descends and thereby impart a step-by-step rotation to said plunger and cutter, and means to raise and lower said pick-up device, said tube having vertical guide slots that receive the ends of said key, the engagement of the end portions of said key within said slots of said tube causing the operation of the pick-up device to impart a step-by-step rotation to said outer jacket.

3. In an automatic drilling tool, a jacket adapted to rest on the bottom of the well, a tube slightly less in diameter than said jacket, said tube having an enlarged externally threaded upper portion screwed into said jacket, the lower portion of said tube being longitudinally slotted and slightly spaced away from the inner wall of said

jacket, a reciprocatory plunger within said jacket, a key carried by said plunger and projecting therefrom through the slotted portion of said tube, a reciprocatory pick-up device having a beveled shoulder adapted to strike said key and to impart rotation to said jacket and plunger, and means to raise and lower said pick-up device.

In testimony whereof I have hereunto signed my name in the presence of two subscribing witnesses at Los Angeles, in the county of Los Angeles and State of California, this 16th day of April 1910.

WILLIAM KAHLE.
